CLAIM

We claim the ornamental design for a fodder-growing enclosure, as shown and described.

DESCRIPTION

FIG. 1 is a perspective view of a fodder-growing enclosure, showing our new design in a closed configuration;
FIG. 2 is a reduced-size exploded perspective view thereof, illustrating an internal rack assembly that includes a plurality of racks supported by brackets of the design;
FIG. 3 is a front elevational view of FIG. 1, the rear elevational view being a mirror image thereof;
FIG. 4 is a cross-sectional view thereof, taken generally along lines 4-4 of FIG. 3;
FIG. 5 is a top plan view of FIG. 1;
FIG. 6 is a cross-sectional view thereof, the rack assembly omitted for clarity of depiction, taken generally along lines 6-6 of FIG. 5;
FIG. 7 is a left-side elevational view of FIG. 1, the right-side elevational view being a mirror image thereof;
FIG. 8 is a bottom plan view thereof;
FIG. 9 is a left-side elevational view of the rack assembly and brackets of the fodder-growing enclosure, shown separately for clarity of depiction, the right-side elevational view being a mirror image thereof;
FIG. 10 is a front elevational view of FIG. 9, the brackets omitted for clarity of depiction, the rear elevational view being a mirror image thereof;
FIG. 11 is an enlarged perspective view of one of the racks, shown separately for clarity of depiction;
FIG. 12 is an enlarged front elevational view of the bracket, shown separately for clarity of depiction, as taken along lines 12-12 of FIG. 6;
FIG. 13 is a left-side elevational view of FIG. 12, the right-side elevational view being a mirror image thereof;
FIG. 14 is a bottom plan view of FIG. 12;
FIG. 15 is a rear elevational view of FIG. 12;
FIG. 16 is a top plan view of FIG. 12; and,
FIG. 17 is a rear exploded perspective view thereof, the rack assembly and rear doors omitted for clarity of depiction. The broken lines depict elements forming no part of the claimed design.
